UNITED STATES PATENT OFFICE.

LOUIS C. BLUME, OF CHICAGO, ILLINOIS.

RADIODETECTOR.

Application filed June 28, 1923. Serial No. 648,305.

My invention relates, generally, to improvements in detectors for use in connection with wireless telephone apparatus and has particular reference to the so-called 5 "cat-whisker" or galena detectors for wireless telephone receiving sets.

In using the ordinary "cat-whisker" or galena detector, considerable difficulty is usually experienced in locating the most sensitive or effective spot with the cat-whisker upon the crystal or other detector bodies. The detectors of the prior art usually require an independent locking means in the nature of a set screw or similar device for 10 locking the cat-whisker in position upon the selected spot of the crystal. It is, therefore, the primary object of my invention to furnish a novel and improved detector of the character set forth, wherein the most sensitive spot of the crystal or detector body may be readily located, an improved clamping means being employed for maintaining the cat-whisker in a selected position.

Another important object of the invention 25 is to furnish a novel and improved support for the cat-whisker, means being provided for a universal movement thereof.

The invention also has for an object to provide a detector of this kind embodying 30 few parts, and which will be highly efficient in use although inexpensive of manufacture.

The above and other objects, which will become more apparent as the description proceeds, are attained by a novel combination 35 and arrangement of parts to be herein-after described and claimed, and in order that the same may be better understood, reference is had to the accompanying drawing forming a part of this specification.

40 In the drawing,

Figure 1 is an elevation of a detector constructed in accordance with my invention;

Fig. 2 is an end elevation thereof;

Fig. 3 is a side elevation of the support, 45 partly broken and partly in section, showing the cat-whisker attachment and associated members, and

Fig. 4 is a detail illustrating the head for supporting the cat-whisker.

50 Referring specifically to the drawing, wherein for the purpose of illustration the preferred embodiment of the invention is disclosed, and in which like reference characters have been used throughout to designate similar parts, numeral 5 denotes a base of insulating material, upon the upper face

of which is supported a support 6 which is fastened to the base by means of a binding post 7 extending through a bottom lateral flange of said support 6. The usual nut and washer 8^a clamping above the lateral portion of the support 6 to maintain the same in place, while a suitable cap nut 8 serves to secure wires to the binding post in the usual manner.

The upper portion of the support 6 terminates in an arcuate portion 9 of substantially 60 180 degrees, this portion being provided with a closed arcuate slot 10 as best shown in Fig. 3 for the reception of a laterally projecting 65 arm 11 for sliding movement therein. The arm 11 is provided with a head 11^a which engages with the inner face of the arcuate portion 9 adjacent the slot 10; while a washer 11^b urged against the outer face of the 70 arcuate portion 9 serves to maintain the arm 11 in a predetermined position. The pin 11 is provided adjacent its outer end with a transverse aperture through which extends 75 for sliding movement a carrier pin 13, which latter is provided at its lower end with a circumferential groove 13^a whereby a contact or cat-whisker carrying head may be attached as will presently appear, and at its 80 upper end with a cap or finger piece 14.

The cat-whisker carrying head is denoted 85 at 15 and is provided with a portion for engagement with the groove 13^a of the pin 13. In the drawings, I have illustrated the head 15 as being substantially U-shaped and provided with a slot 15^a in one of its arms for engaging the groove 13^a of the pin 13. The other arm is adapted to carry upon its outer face the contact wires or cat-whiskers 16 as shown in Figs. 3 and 4. More specifically the head 15 is formed from a single length of more or less resilient metal bent or otherwise arranged in U-shaped formation and having one of the branches formed 90 with a longitudinal slot which extends out through one end thereof to define a pair of legs which engage in the circumferential groove 13^a and thereby hold the U-shaped head in proper position. It will be seen 95 that the U-shaped member 15 may be freely disconnected when desired.

A plate 17 carried adjacent the other end 100 of the upper face of the insulated block 5 supports a metallic cup 18, the outer surface of which is knurled as shown at 19, the detector body 20^a being secured or 110 clamped therein by means of a set screw 20

passing through the side wall of the cup 18. The detector body may be of sulphuret of lead, commonly called galena, or any other suitable crystal mass commonly used 5 for this purpose. The plate 17 is fastened to the insulated block 5 by means of the second binding post 22 which passes through a longitudinal slot 21 in the end of the plate. The usual washer and nut 22^a and 22^b, respectively, serve to clamp the plate in a predetermined position. The cap nut 23 acts to secure wires to the binding post 22.

From the foregoing description, the construction of my detector will be readily appreciated by those skilled in the art. Its 15 operation may be briefly summarized as follows:

The detector is coupled in an electrical circuit with other elements of a wireless 20 telephone receiving set by means of the binding posts 7 and 22. The crystals or other detector body substance 20^a of high electrical conductivity is clamped in the cup 18 by means of the set screw 20. The contact 25 surface or face of this detector body is preferably of a very rough character, thereby providing a multiplicity of minute contact surfaces and materially increasing the general utility and serviceability of the device.

The electro-radiant waves are transmitted 30 through the detector body or crystal portion 20^a and the cat-whisker 16, from whence they pass to the receiver, the wave oscillations being converted into a form for intelligently transmitting the message without 35 necessitating the use of any auxiliary energy. The operator, owing to the universally movable mounting of the cat-whisker through the medium of the vertically slidable pin 13 and the arcuately slidable pin 11 which may be rotated in the slot 10 of the support 6, may brush the metal contact 40 elements or cat-whiskers 16 over the face of the crystal or detector body 20^a and effectively locate the most sensitive spot therein.

Figures 1 and 3 plainly illustrate that the upper portion of the supporting member 6 is provided with a return bend and the slot 10 is in this return bend so that, if

desired, the laterally projecting arm 11 may be swung up to permit the cat whisker carrying head 15 to be easily disconnected or reapplied to the pin 13. In other words the cat whisker carrying head 15 may be removed a substantial distance from the crystal or piece of galena as contact of the hand with the galena frequently destroys the sensitivity of the galena.

The spring 12 functions to tightly press 50 against the pin 13 and the washer 11^b, thus serving to hold the pins 13 and 11 in the desired position. While the preferred embodiment of my invention has been described and illustrated in accordance with the patent statutes, yet it will be understood that 55 various changes and modifications may be made therein without departing from the spirit of my invention, the scope of which is defined by the following claims.

Having thus described my invention, what 70 I claim as new and desire to secure by Letters Patent is:

1. In a radio device, the combination of 75 a carrier having a circumferential groove adjacent one end thereof, of a U-shaped head having a branch formed with a slot opening out through one end thereof and defining a pair of legs to engage in said circumferential slot to connect the head to said carrier member, said U-shaped head 80 having a second branch, and a cat whisker carried by said second branch.

2. In a radio device, the combination of 85 a carrier member having a circumferential groove adjacent one end thereof, of a U-shaped head formed from a single length of resilient material having a branch formed with a longitudinal slot opening out through one end thereof and defining a pair of legs to engage in said circumferential slot to connect the head to said carrier member, said U-shaped head having a second branch, approximately parallel to the first named 90 branch and a cat whisker carried by said second branch.

In testimony whereof I affix my signature.

LOUIS C. BLUME.
